UNITED STATES PATENT OFFICE.

JULIUS LARSEN, OF COPENHAGEN, DENMARK.

SEWING-MACHINE.

1,172,373.

Specification of Letters Patent. Patented Feb. 22, 1916.

Application filed July 16, 1912. Serial No. 709,806.

To all whom it may concern:

Be it known that I, JULIUS LARSEN, a subject of the King of Denmark, residing at Copenhagen, Denmark, Frederik VII's Gade No. 13, have invented certain new and useful Improvements in Sewing-Machines, of which the following is a specification.

The present invention refers to a device in sewing machines for sewing both thick and thin work.

The special characteristic feature of the invention consists of a radial support for the bow-shaped needle, making it possible to use a bow-shaped or bent needle for sewing, without respect to the nature or thickness of the piece of work to be sewn.

Bow-shaped or bent needles, of the ordinary machine needle type, with an eye in the point, have hitherto not been used, notwithstanding that in many cases they would remedy a great deficiency in sewing machines both for thin and thick leather work, and this is doubtless due to the fact that for fine work the needle must be very fine and in many cases very much bent; but for thick work requiring a curved needle, a so-called hook needle has been used which has a hook in its point. This kind of needle cannot however be used as a needle in the common meaning of the word—an instrument which punctures the work—but it is only used as a catch or hook which carries the thread through a hole already punctured in advance by means of a square awl.

The difficulty in using fine, strongly curved needles, consists in the pressure between the point and the needle-holder, being exerted in the direction of the chord of the needle's arc, and the object of the present invention is to give the needle an extra support at the central point of the arc, thus relieving the tension at this point and preventing the needle from breaking. This makes it possible to use a bow-shaped or curved needle in sewing even the thickest leather work, without the previous use of an awl.

This invention is shown on the accompanying drawing, which shows a sewing machine furnished with this device.

Figure 1 is a side view of the machine. Fig. 2 is a front view of the same.

On an upright bar 1 there is disposed a sliding collar 2, which can be moved up and down by means of a crank pin 5 on the axle 3, the crank pin 5 being surrounded by a

block 4 which travels in a slide 6 on the collar 2. On the collar there are disposed shoulders 7, which form a bearing for the arm 8, which by means of a pin 9 is movably connected with the shoulders. The lower end of the arm 8 is by means of a pin 10 connected with the needle holder 11, which is pivoted on the pin 12. The outer end of the needle holder where the bow-shaped, or curved needle is arranged, will thus describe an arc of a circle whose center is the pin 12.

On the pin 12 there is movably disposed a needle guide or support 14, which has a slide 15 surrounding the needle 13. This needle guide or support 14 can travel downward until it reaches the pressure foot 15, but its upward movement is by means of a stop 25 restricted to the position shown in Fig. 1.

The presser or pressure foot 15 is fixed to the pin 12, and on this pin there is also fixed a beak 16. The free end of this beak slides on a sloping plane on the block 17, which can move back and forth under the effect of the arm 18, disposed on the axle 19, which passes through a slide or slot in the collar 2. On the other end of the axle 19 there is an arm 22, whose free end presses against a cam on the axle 3, against which it is held pressed by a spring 20. Under the pressure foot 15 there is disposed on the outer side of the sliding cover, a feeder, whose point 21 is moved up and down and sideways by means of suitable mechanism from the axle 3. By the movement of the arm 18 the block 17 is pushed to the left and lifts the beak 16, causing the pressure foot 15 to press down the piece of work firmly. Then the collar 2 passes downward and presses by means of the arm 8 against the needle holder 11.

At the moment when the point of the needle touches the piece of work, which offers resistance to the further passage of the needle, there occurs a tension on the curved needle, but this tension is relieved by the needle support or guide 14, the arc of the bow-shaped needle being preserved unaltered and the point of the needle being forced through the piece of work, while the needle support or guide accompanies the needle until it has reached the pressure foot 15, where it remains. On the upward movement of the needle, either the needle itself or a little spring 24 will press the needle

support or guide up into the position shown in Fig. 1. After this the block 17 returns to its original position and the beak is thereby caused to release the pressure foot 15, so 5 that the feeder can feed the work forward.

The needle guide must accompany the needle during its downward movement as when the point of the needle presses against the leather the curvature of the needle is 10 increased owing to the pressure of the needle holder and as the hole in the needle guide fits nicely for one curvature of the needle the needle cannot pass freely when the curvature is slightly changed and the needle 15 guide will therefore move downward together with the needle. When using needles with various arcs the needle guides must be changed as only one guide can be used in connection with a needle having a 20 particular arc.

What I claim, and desire to secure by Letters Patent, is:

1. In a sewing machine, a needle holder, a curved needle held by said needle holder, a presser foot serving as a guide for the needle, and a freely movable guide disposed between the presser foot and the holder which, if the curvature of the needle alters under pressure, moves downward owing to the

pressure of the needle and supports the needle during its penetration of the work. 30

2. In a sewing machine, a needle holder, a curved needle held by said needle holder, a presser foot serving as a guide for the needle, a freely movable guide disposed between the presser foot and the holder, which, if the curvature of the needle alters under pressure, moves downward owing to the 35 pressure of the needle, and a spring for returning the guide to its normal position 40 when the needle assumes its normal curvature.

3. In a sewing machine, a needle holder, a curved needle held thereby, a presser foot also serving as a guide for the needle, a 45 guide serving to support the needle between the holder and the presser foot, an upright bar forming part of the machine, a collar slidably mounted on said bar, means for moving said collar, and a pivoted bar connecting said collar with the needle holder 50 for operating the latter.

In testimony whereof I affix my signature in presence of two witnesses.

JULIUS LARSEN.
